UNITED STATES PATENT OFFICE.

PERRY E. MACK, OF MILWAUKEE, WISCONSIN.

OIL-PUMP.

1,001,872.

Specification of Letters Patent. Patented Aug. 29, 1911.

Application filed January 19, 1911. Serial No. 603,424.

To all whom it may concern:

Be it known that I, PERRY E. MACK, a citizen of the United States, residing at Milwaukee, in the county of Milwaukee and 5 State of Wisconsin, have invented certain new and useful Improvements in Oil-Pumps, of which the following is a specification, reference being had to the accompanying drawing, forming a part thereof. 10 This invention relates to apparatus for automatically feeding oil or the like in predetermined quantities to bearings or parts to be lubricated. Its main objects are to produce a durable oil pump having few 15 and simple parts, requiring little or no care or attention, and reliable in operation, to provide such a pump with a simple adjustment for varying the feed if desired, and generally to simplify and improve the construction and operation of lubricating 20 pumps of this class.

It consists in the construction, arrangement and combination of parts as herein-after particularly described and pointed out 25 in the claims.

In the accompanying drawing like parts are designated by the same characters in the several figures.

Figure 1 is an axial section on the line 30 1—1, Fig. 2, of a pump embodying the invention, and Figs. 2 and 3 are cross sections thereof on the lines 2—2, and 3—3, respectively, Fig. 1.

The pump barrel or cylinder *a*, which 35 may be formed integrally with a head *b* at one end and closed by a screw cap or removable head *c* at the other end, has on opposite sides thereof adjacent to the head *b*, as shown in Figs. 1 and 2, suction and discharge ports *d* and *e*, which are connected by pipes (not shown) or otherwise, with an oil reservoir on the one hand and with one or more bearings or parts to be lubricated on the other hand.

40 A reciprocable and rotatable piston or plunger *f* fitted in the cylinder *a*, is formed on one side at the end adjacent to the head *b* with a valve and cam projection *g*, which is adapted to alternately cover and uncover the ports *d* and *e* when the plunger is rotated. The outer end of this projection, which is rounded or inclined, as shown in Fig. 1, is adapted by engagement with an 45 internal abutment in the cylinder to impart a reciprocating movement to the plunger as it is turned. For the purpose of varying

the stroke of the plunger and the quantity of oil fed by the pump at each stroke of the plunger, said abutment is made adjustable and may consist, as shown in Fig. 1, of 60 a screw *h* threaded in the head *b* of the cylinder parallel with its axis and secured in adjusted position by a lock nut *i*. By this means the axial movement of the plunger may be varied from zero to full 65 stroke, and a fine adjustment of the feed effected without opening or stopping the pump, the head of the screw *h* being accessible outside the cylinder *a*.

The plunger may be moved toward the 70 head *b* and held in engagement therewith or with the screw *h*, by any suitable means, as by gravity if the cylinder is mounted with its head *b* downward, or in other positions by a spring *j*, bearing at one end 75 against the closed head of the plunger, which may be hollow or tubular, and at the other end against the cap or head *c* or a cylindrical seat *k* loosely fitted in the plunger and centrally pivoted on said cap or 80 head, as shown in Fig. 1.

Various means may be employed to rotate the plunger. A worm *l* fitted to turn in a transverse box or enlargement *m* of the cylinder and meshing with elongated gear 85 teeth *n* in the plunger, is shown in Figs. 1 and 3 for this purpose. The action of the worm in turning the plunger also tends to thrust it toward the head *b* and hold the projection *g* in engagement therewith and 90 with the screw *h*.

The cylinder may be flattened on one side, as shown in Figs. 2 and 3, for attachment to a support, or may have other provision for mounting it according to circumstances. 95

In the operation of the pump, the plunger *f* being turned by the worm *l* in the direction indicated by arrows, Figs. 2 and 3, the projection *g* while it closes the discharge port *e*, engages with the screw *h* and thrusts 100 the plunger away from the head *b*, thereby drawing oil from the reservoir through the suction port *d* into the cylinder. As said projection passes out of engagement with the screw *h* it covers the suction port *d* and 105 uncovers the discharge port *e*. Thereupon the spring *j* thrusts the plunger back toward the head *b* and forces the oil in the cylinder out through the port *e*.

The quantity of oil drawn into and discharged from the cylinder with each complete revolution and reciprocation of the

piston is determined and the feed is regulated by the adjustment of the screw *h*. The more said screw is withdrawn, the less will be the quantity of oil pumped. When 5 the tip of the screw is set flush with or outside the inner face of the cylinder head *b*, there will be no reciprocation of the plunger and hence no feed of oil.

Various modifications in the construction 10 and arrangement of parts of the pump may be made without materially affecting its mode of operation and without departing from the principle of the invention.

I claim:

15 1. In a pump the combination of a cylinder having suction and discharge ports and an inwardly projecting abutment, a piston fitted to simultaneously reciprocate lengthwise and to rotate in said cylinder and 20 provided with a valve and cam projection adapted to alternately cover and uncover said ports and by engagement with said abutment to cause the reciprocation of the plunger, and means for rotating the plunger.

25 2. In a pump the combination of a cylinder having suction and discharge ports and an internal abutment, a reciprocating and rotary plunger fitted in said cylinder and 30 provided with a valve and cam projection adapted to alternately open and close said ports and by engagement with said abutment to cause the reciprocation of the plunger.

ment to thrust the plunger away from the adjacent cylinder head, and a spring tending to move the plunger in the opposite direction. 35

3. In a pump the combination of a cylinder having suction and discharge ports and an internal abutment adjustable lengthwise of the cylinder, a reciprocating and rotary plunger fitted in said cylinder and provided at one end with a valve and cam projection which is adapted to alternately open and close said ports and by engagement with said abutment to move the plunger lengthwise, and means for rotating the plunger. 40

4. In a pump the combination of a cylinder having suction and discharge ports and an internal abutment, a reciprocating and 45 rotary plunger fitted in said cylinder and provided with elongated gear teeth and with a valve and cam projection adapted to alternately open and close said ports and by engagement with said abutment to move the plunger lengthwise, and a worm arranged 50 transversely to the axis of the cylinder in mesh with the gear teeth of the plunger.

In witness whereof I hereto affix my signature in presence of two witnesses.

PERRY E. MACK.
